[57] CLAIM

The ornamental design for a haemodialyzer or the like, as shown and described.

DESCRIPTION

FIG. 1 is a top plan view of a haemodialyzer, showing our new design;

FIG. 2 is a side elevation thereof;

FIG. 3 is a right end elevation thereof; and

FIG. 4 is a bottom isometric view thereof.

Fig. 1.Fig. 2.Fig. 3.Fig. 4.
